BY
Edgar D. Elliott
ATTORNEY'S

UNITED STATES PATENT OFFICE.

WILLIAM HENRY ELLIOTT, OF RED BANK, NEW JERSEY.

DESIGN FOR A SEWER'S TREE.

SPECIFICATION forming part of Design No. 28,473, dated April 12, 1898.

Application filed January 18, 1898. Serial No. 667,115. Term of patent 14 years.

To all whom it may concern:

Be it known that I, WILLIAM HENRY ELLIOTT, a citizen of the United States, residing at Red Bank, in the county of Monmouth and State of New Jersey, have invented and produced a new and original Design for a Sewer's Tree, of which the following is a specification, reference being had to the accompanying drawing, forming part hereof.

10 The novel design forming the subject of this invention is shown in perspective in the said drawing.

Said design comprises a circular base 1, from the center of which rises a post 2. At 15 the upper end of the post 2 is a circular head 3, extending in a plane approximately at right angles to the post 2, while the upper and outer face is curved or rounded. At the center and on the top side of the head 3 is a concentric 20 figure 4, having a curved or rounded face on a different curvature, however, from the curve

of the face of the head. Around the said figure 4 and uprising from the head are a plurality of bosses 5, and near the outer periphery of the head 3 the radially-extending projections 25 or hooks 6 are shown.

The said design is novel, effective, and pleasing to the eye and furnishes an ornamental and attractive figure.

Having fully described my invention, I claim as new and desire to secure by Letters Patent—

The design for a sewer's tree, substantially as shown and described.

In testimony that I claim the foregoing as my invention I have signed my name, in presence of the subscribing witnesses, this 15th day of January, 1898.

WILLIAM HENRY ELLIOTT.
